UNITED STATES PATENT OFFICE.

MILAN H. FISHER, OF CHICAGO, ILLINOIS, ASSIGNOR TO H. L. FISHER MFG. CO., INC., OF CHICAGO, ILLINOIS, A CORPORATION OF ILLINOIS.

STEREOTYPER'S CASTING MACHINE.

Application filed October 27, 1922. Serial No. 597,386.

To all whom it may concern:

Be it known that I, MILAN H. FISHER, a citizen of the United States, residing at Chicago, in the county of Cook and State of Illinois, have invented certain new and useful Improvements in Stereotypers' Casting Machines, of which the following is a specification.

My invention relates to a stereotyper's casting machine and more particularly to a machine having a pair of spaced platens against one of which the matrix is placed, being held thereagainst by suitable gauges which serve to confine the molten metal to the desired space between the platens.

One of the objects of my invention is the provision of a machine of simple and rugged construction, inexpensive to manufacture, and which may be easily handled in making castings.

In its preferred form my invention contemplates a supporting frame having substantially horizontal and vertical portions; and, a further object of my invention is the provision of a pair of platens and suitable clamping means therefor so arranged that the platens may be placed either in a substantially horizontal or vertical position against the respective frame portions by which arrangement the upper platen may be swung to the vertical position and the lower platen to the horizontal position, the matrix and gauges placed as desired on the inner face of the lower platen, then the upper platen lowered onto the gauges and the two platens clamped together. When the platens are clamped together, the matrix and gauges are firmly held in position and the two platens may then be swung into the vertical position and molten metal poured into the chamber thus provided and the casting made.

It is a further object of my invention to provide an arrangement whereby the distance between the platens may be varied to make castings of different thicknesses, for example, type-high or thin-plate, the latter commonly being termed "skivers", suitable gauges, of course, being provided for the respective castings. This object may be accomplished by pivotally attaching the upper platen at one end directly to the supporting frame, while the lower platen is indirectly connected at one end to the supporting frame by means of a pair of links, means be-

ing employed to clamp the platens together at the other end.

Another object of my invention is the provision of means whereby not only the distance between the platens may be varied to make castings of different thicknesses but which will be so arranged that the two platens may be brought together, regardless of the height of the gauge bars, without one being shifted longitudinally relative to the other, thus reducing to a minimum any tendency for the gauge bars and matrices to be shifted out of place when the platens are being brought into operative relationship. In one form of my invention either the pivoted connection between the links and the frame or that between the links and the lower platen is made adjustable. In another form of my invention L-shaped links are provided for connecting the lower platen to the supporting frame, and adjusting screws are associated with the respective links in such manner that the inner end of the lower platen may be raised or lowered, when in the horizontal position, relative to the other platen so that the upper platen may be swung down onto the gauges and locked to the lower platen without moving the latter platen.

A further object of my invention is the provision of a metal pot tiltably mounted on the vertical frame portion in combination with means for heating the metal pot, so that molten metal may flow directly from the pot into the casting chamber when the platens are swung upwardly into a vertical position.

A further object of my invention is the provision of novel quick-acting means, preferably adjustable, for clamping the two platens together.

The invention consists in the novel constructions, arrangements and devices to be hereinafter described and claimed for carrying out the above stated objects and such other objects as will appear from the following description of certain preferred embodiments illustrated in the accompanying drawings, wherein—

Fig. 1 is a perspective view of a machine embodying the principles of my invention, the lower platen being in the horizontal position and the upper platen in the vertical position;

Fig. 2 is a side elevational view of a frag-

mentary portion of the machine, the two platens being shown clamped together and in the horizontal position;

Fig. 3 is a plan view of a fragmentary portion of the machine looking down upon the platens when they are in the position shown in Fig. 2;

Fig. 4 is a sectional view, on an enlarged scale, taken on the line 4—4 of Fig. 2;

Fig. 5 is a perspective view of the machine showing the platens in the vertical position ready for the metal to be poured into the casting chamber therebetween;

Fig. 6 is an elevational view, on an enlarged scale, of the preferred means of locking the platens together;

Fig. 7 is a sectional view taken on the line 7—7 of Fig. 6;

Fig. 8 is a side elevational view of the machine, similar to Fig. 2, but showing the platens relatively close together for making thin-plate castings;

Fig. 9 is a side elevational view of a fragmentary portion of a machine illustrating a modified arrangement of connecting the platens with the supporting frame; and

Fig. 10 is a sectional view taken on the line 10—10 of Fig. 9.

Like characters of reference designate like parts in the several views.

Referring now to the accompanying drawings, the supporting frame includes a rectangular framework comprising longitudinally extending members 12 connected by transversely extending members 13 and 14, the frame being mounted on legs 15. A pair of vertically extending frame members 16 are mounted on the respective frame members 12, being secured thereto by bolts 17, see Figs. 2, 3 and 5.

In the embodiment illustrated in Figs. 1 to 8, inclusive, the frame members 16 on their inner sides have aligned recesses 18, see Fig. 4, for the reception of the extremities of a horizontally transversely extending rod 19. The upper platen 20 is provided on its inner or lower side with lugs 21 which are perforated for the reception of the rod 19. A pair of L-shaped link members 22 is provided, each of said link members being perforated at one end for the reception of the rod 19 and at the other end for the reception of fastening members 23 carried by the lower platen 24. The rod 19 is inserted through the lugs 21 of the upper platen and the links 22 are placed in position on said rod before the second frame member 16 is secured in place on the adjacent frame member 12.

In Fig. 1 the platens are in what may be termed the "make-up" position, the upper platen being in a vertical position and the lower platen in a horizontal position. The platens are held in spaced relationship and the molten metal is confined in the casting

chamber formed therebetween by gauges of any desired construction. In the embodiment illustrated, the gauges comprise longitudinally extending bars 25 and a transversely extending bar 26. Each of the bars 25 carries a bracket 27 so arranged that, when the inner or lower sides of the brackets bear against the bar 26, the bars 25 are at right angles to the bar 26 and the casting will be square on three sides. The bars 25 may be moved toward or away from each other so that castings of various widths may be made.

The matrix (not shown) is placed against the upper side of the lower platen 24, and the gauge bars are placed thereover in the desired position. Each of the links 22 is provided with a tapped recess 28, see Fig. 2, for the reception of an adjusting screw 29. The adjusting screws 29 are adapted to engage the under side of the lower platen 24 when said platen is in horizontal position. When the platen 24 is in said position, it rests upon the adjusting screws 29, fastening members 23 pivoted in the outer ends of the links 22, and the seat 13^a which is secured to or made an integral part of the transverse frame member 13. The adjusting screws 29 are set so that the distance from the plane of the upper sides of the gauge bars to the axis of the rod 19, when the platen 24 is in the horizontal position, is substantially equal to that from the plane of the lower side of the platen 20 to the axis of said rod. The upper platen, therefore, may be swung down against the upper faces of the gauge bars without causing any movement of the lower platen and without causing the gauge bars themselves to shift on the lower platen.

The two platens may be locked together in any desired manner, but I prefer to use a pair of adjustable and quick-acting clamps of the construction shown in the drawings, see particularly Figs. 6 and 7. I preferably provide on each side of the lower platen a fastening member 30 having a vertically extending portion 30^a and a horizontally extending portion 30^b. The portion 30^a is provided with a vertically extending slot 31 through which a screw 32 may be inserted, said screw being threaded into a suitable recess provided in the side of the platen. The portion 30^b is tapped for the insertion of a set screw 33 which is adapted to engage the bottom or outer side of the platen. Links 34 are attached at their lower ends to the fastening member 30 by a bolt 35. A cam member 36 is attached to the upper ends of the links by a bolt 37, adapted to extend through the apertures 34^a or 34^b of the links, said cam member having a handle portion 36^a. The upper platen is provided with a lug 38 projecting laterally from each side, these lugs being so positioned that they

may be straddled by the respective pairs of links 34 and they are also arranged so that they form seats for the respective cam members 36.

- 5 When the platens are in the position shown in Fig. 2, and the clamping members are swung around to bring the cam members into engagement with the seats on the respective lugs 38, the platens will be securely locked together, as shown in Figs. 2 to 8, inclusive. By loosening the screws 32, the respective fastening members 30 may be adjusted relative to the upper platen by turning the screws 33, the fastening members 15 being secured in the desired position by turning home the screws 32.

After the platens have been locked together in the manner described, they may then be swung from the horizontal position shown in Fig. 2 to the vertical position 20 shown in Fig. 5, or vice versa. A latch member 39 is pivotally attached to one of the frame members 16 is adapted to engage a catch 40 provided on one of the platens 25 to hold the platens in the vertical position.

A metal pot 41 is pivotally mounted on the frame members 16 in such manner that the molten metal may flow therefrom, through the spout 41^a thereof, directly into the casting chamber formed between the two platens. The pot and the metal therein are preferably heated by suitable burners 42 connected with a source of gas or gasoline.

In Fig. 2 type-high gauges are shown in place between the two platens. The adjusting screws 29 in such case project only a relatively short distance out of the links 22. In Fig. 8, thin-plate gauges are shown in position between the two platens and the adjusting screws 29 are shown as extending a considerable distance out of the arms 22 so that the inner end of the lower platen will be raised sufficiently to make the distance from the plane of the upper sides of the thin-plate gauges to the axis of the rod 19, when the lower platen is in the horizontal position, substantially equal to that from the plane of the lower side of the platen 20 to the axis of the rod 19. When thin-plate gauges are used, the bolt 37 is removed from the apertures 34^a and inserted through the apertures 34^b to clamp the platens together in closer relationship. An adjustable connection is provided, therefore, between the links 34 and the cam member. Any inaccuracies in manufacture or wear may be taken care of by loosening the screws 32 adjusting the screws 33, and then turning the screws 32 home.

60 In Figs. 9 and 10 a modified arrangement of connecting the two platens to the framework is illustrated. In this embodiment a pair of standards 43 is secured by screws 44 to the frame members 12. The upper ends 65 of said standards are perforated for the re-

ception of a transversely extending rod 45. The upper platen 46 is provided with a pair of perforated lugs 47 through which the rod 45 may be inserted. A pair of links 48 perforated at their upper ends are placed on the rod 45. In this embodiment the lower platen 49 is also provided with a pair of perforated lugs 50. Each of the links 48 adjacent their lower ends is provided with perforations 48^a and 48^b adapted to receive a screw 51. When type-high castings are to be made, the screws 51 are inserted through the perforations 48^b and, when thin-plate castings are to be made, they are inserted through the perforations 48^a of the respective links 48. An adjustable connection is, therefore, provided between the links 48 and the platen 49. The platens are clamped together and the machine is operated in a manner similar to the embodiment hereinbefore described.

I do not intend to limit my invention to the details of construction shown and described herein, except only in so far as certain of the appended claims are specifically so limited, as it will be obvious that various modifications may be made by those skilled in the art without departing from the principles of the invention.

I claim:

1. A stereotyper's casting machine comprising a supporting frame, a pair of platens, one of said platens being pivotally connected to said frame, a pair of links pivotally connected at one end to said frame so as to swing about the axis of the pivotal connection first named, the other of said platens being pivotally connected to the other end of said links, and means for locking said platens together.

2. A stereotyper's casting machine comprising a supporting frame, a pair of platens, one of said platens being pivotally connected to said frame, a pair of links pivotally connected at one end to said frame so as to swing about the axis of the pivotal connection first named, the other of said platens being pivotally connected to the other end of said respective links, means for limiting pivotal movement of said last named platen relative to said links, and means for locking said platens together.

3. A stereotyper's casting machine comprising a supporting frame including a horizontally extending rod, a pair of platens, one of said platens being swingingly connected at one end to said rod, a pair of links, said respective links being pivoted at one end on said rod, the other of said platens being pivotally connected to the other end of said respective links, and means for locking said platens together.

4. A stereotyper's casting machine comprising a supporting frame, a pair of platens, one of said platens being pivotally connected to said frame, a pair of L-shaped

- links, said respective links being pivotally connected at one end to said frame so as to swing about the axis of the pivotal connection first named, the other of said platens 5 being pivotally connected to the other end of said respective links, adjusting screws associated with said respective links and said last-mentioned platen, and means for locking said platens together.
- 10 5. A stereotyper's casting machine comprising a supporting frame including a horizontally extending rod, a pair of platens, one of said platens being swingingly connected at one end to said rod, a pair of 15 L-shaped links, said respective links being pivoted at one end on said rod, the other of said platens being pivotally connected to the other end of said respective links, adjusting screws associated with said respective links and said last-mentioned platen, and means for locking said platens together.
- 15 6. A stereotyper's casting machine comprising a supporting frame, a pair of platens, one of said platens being pivotally connected to said frame, a pair of links pivotally connected at one end to said frame so as to swing about the axis of the pivotal connection first named, said links at the other end being connected to the other of said platens, one of said two last named connections being adjustable, and means for locking said platens together.
- 20 7. A stereotyper's casting machine comprising a supporting frame including a horizontally extending rod, a pair of platens, one of said platens being swingingly attached at one end to said rod, a pair of links pivotally connected at one end to said rod and at the other end to the other of said platens, one of said connections being adjustable, and means for locking said platens together.
- 25 8. A stereotyper's casting machine comprising a supporting frame, a pair of platens, one of said platens being pivotally connected to said frame, a pair of links pivotally connected at one end to said frame so as to swing about the axis of the pivotal connection first named, the other of said platens 30 being pivotally connected to the other end of said links whereby said platens may be swung from a horizontal to a vertical position, or vice versa, means for locking said platens together, and a container for molten metal mounted on said
- frame and so arranged that molten metal may flow therefrom into the casting chamber when said platens are in the vertical position.
9. In a stereotyper's casting machine, the combination of a pair of platens, and means to clamp said platens together comprising a link pivotally connected at one end to one of said platens, and a cam member pivotally connected to the other end of said link, the other of said platens having a seat adapted to receive said cam member.
10. In a stereotyper's casting machine, the combination of a pair of platens, and means to clamp said platens together comprising a cam member, and a link pivotally connected at one end to one of said platens and at the other end to said cam member, one of said connections being adjustable, the other of said platens having a seat adapted to receive said cam member.
11. In a stereotyper's casting machine, the combination of a pair of platens, a fastening member adjustably connected to one of said platens, a cam member, and a link pivotally connected at one end to said fastening member and at the other end to said cam member, the other of said platens having a seat adapted to receive said cam member.
12. In a stereotyper's casting machine, the combination of a pair of platens, a fastening member adjustably attached to one of said platens, a cam member, and a link pivotally connected at one end to said fastening member and at the other end to said cam member, one of said connections being adjustable, the other of said platens having a seat adapted to receive said cam member.
13. In a stereotyper's casting machine, the combination of a pair of platens, an L-shaped fastening member one leg of which is provided with a slot and the other of which is perforated and screw-threaded, fastening means carried by one of said platens and projecting through said slot, an adjusting screw projecting through said perforation and abutting against the last-mentioned platen, a cam member, and a link pivotally connected at one end to said fastening member and at the other end to said cam member, the other of said platens having a seat adapted to receive said cam member.

MILAN H. FISHER.
